FIG. 8. FIG. 9. Inventor
I. O. Anderson.

By *A. Randolph Jo* Attorney

UNITED STATES PATENT OFFICE.

IRVIN O. ANDERSON, OF TRINIDAD, COLORADO.

VARIABLE-INDUCTANCE TUNER.

Application filed December 7, 1922. Serial No. 605,445.

To all whom it may concern:

Be it known that I, IRVIN O. ANDERSON, a citizen of the United States, residing at Trinidad, in the county of Las Animas and 5 State of Colorado, have invented certain new and useful Improvements in Variable-Inductance Tuners, and I do hereby declare the following to be a full, clear, and exact description of the invention, such as will 10 enable others skilled in the art to which it appertains to make and use the same.

The invention has for its primary object the provision of a device for varying the inductance in a radio transmitter or receiver 15 circuits to change the wave length and allow for tuning, and aims to provide a device which may be easily constructed and which is compact and which may be readily installed and readily adjusted to meet existing 20 conditions and requirements.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without 30 departing from the nature of the invention.

Referring to the accompanying drawings forming a part of the application,

Figure 1 is an elevation of a device embodying the invention,

Figure 2 is a section thereof on the line 2-2, of Figure 1.

Figure 3 is an elevation of the rotary member,

Figure 4 is a diagrammatic view of the 40 rotary member and connections,

Figure 5 is a detail view of the separable plate for securing the operating stem to the rotary member,

Figure 6 is a view similar to Figure 1 of a 45 modification,

Figure 7 is an edge view of the modification,

Figure 8 is a view similar to Figure 3 of the 50 rotary member embodied in the modification, and

Figure 9 is a diagrammatic view of the modified form of rotary member and connections associated therewith.

Corresponding and like parts are referred 55 to in the following description and de-

signated in the several views of the drawings by like reference characters.

The device comprises an outer stationary member and an inner rotary member, each of the members embodying a coil of wire, 60 and the coils of both members may be in series, as indicated in Figure 1, and the detail views thereof are adapted to be independently coupled, as indicated in Figure 6 and the detail views thereof. A vital 65 feature of the structure, however, resides in having both members of flat form for compactness, cheapness of construction and ease of installation and adjustment when tuning. The general outline of the members 70 is immaterial but it is preferred to have the rotary member of circular form, but the outer member may be of rectangular form, as indicated in Figure 1, or of circular outline, as indicated in Figure 6. 75

Referring to Figure 1 and the detail views thereof, the outer member is designated by the numeral 1 and comprises two rectangular plates of insulating material disposed in parallel relation and spaced apart a suitable 80 distance, blocks 2 being interposed therebetween and preferably disposed at the corners whereby to provide ample room for the rotary member. Wire of suitable gage is wound about the member 1 to form a coil 3 85 and a terminal of such wire is connected to a binding post 4. The other terminal of the wire is connected to a plate 5 secured to a side of the frame comprising the member and provided with a threaded opening 1. 90 The side plates comprising the frame are thin for lightness, compactness and neatness.

The rotary member 6 is flat and preferably of circular outline and is of a size to fit 95 within the member 1 and turn freely. A wire is wound about the rotary member 6 to form a coil 7 and one end of said wire is connected to a plate 8 upon one side of the member 6 and the other end is connected to a plate 9 upon the opposite side of the member. A trunnion screw 10 engages the threaded opening in plate 5 and also engages an opening in plate 8 and a wire 11 connects the elements 5 to a binding post 12. 100 A stem 13 connects the element 9 with a plate 15 to which an end of the wire forming the coil 3 is connected, with the result that the two coils 3 and 7 are connected in series, having the two binding posts 4 and 110

12, whereby to couple the device when operatively positioned in a set. The inner end of the stem 16 is of non-circular form and fits a socket of corresponding shape formed 5 in a side of the member 6, whereby rotation of the stem 13 in either direction effects a corresponding rotation of the member 6. An annular groove 17 formed adjacent the inner end of the stem 13 receives the plate 10 15, whereby the stem is held in position. As shown most clearly in Figure 5, the plate 15 is formed of sections notched in their inner or meeting edges to snugly fit the annular groove 17 of the stem 13 whereby displacement 15 of the latter is prevented after the plate 15 has been made secure to the outer side of the casing comprising the member 1.

In the construction shown in Figure 6, the outer member 1^a is of circular outline, being 20 otherwise substantially the same in construction as the member 1 and having a wire wound thereabout to form a coil 3. Binding posts 19 and 20, applied to the frame or casing of the member 1^a, have opposite 25 ends of the wire forming the coil 3 connected thereto.

The rotary member 6^a is similar to the corresponding member 6 and has a wire wound thereabout to form a coil 7. Plates 30 21 and 22, attached to opposite sides of the member 6^a, have opposite ends of the wire forming the coil 7 connected thereto. A trunnion screw 23, pivotally connecting the member 6^a to the member 1^a, is connected to 35 a binding post 24 by means of a wire 25, and a plate 15 is electrically connected to the

plate 22 by means of a stem 13 and a wire 26. connects said plate to a binding post 27. The parts 15 and 13 are substantially the same as corresponding parts shown most 40 clearly in Figures 4 and 5. It will thus be understood that the modified structure is adapted to have the coils 3 and 7 independently connected.

The flat formation of the members is important for simplicity and cheapness of structure, compactness and ease of installation selectivity when tuning the transmitter or receiver of a radio wireless. 45

What is claimed is:

In a radio variable inductance, an outer flat member, an inner flat member rotatable relative to the outer member, inductance coils wound around said members, a trunnion screw mounted in one side of the outer 55 member and in supporting relation with the inner member, a stem mounted in the opposite side of the outer member and having connection with the inner member to rotate therewith and form a support therefor, and a plate attached to a side of the outer member and engaging said stem to retain it in given position, said trunnion screw and stem operating to electrically connect the wires forming the coils surrounding the two 60 members.

In testimony whereof I affix my signature in presence of two witnesses.

IRVIN O. ANDERSON.
